ROSCOE C. ZUCKERMAN, OF STOCKTON, CALIFORNIA

ADHESIVE TAPE CONTAINER AND CUTTER

Application filed February 19, 1930. Serial No. 429,565.

This invention relates to adhesive tape or plaster of what is commonly known as the surgical type. Such tape is put out in roll or spool form and its nature is such that it is practically impossible to tear it across. A knife or scissors are therefore at present necessary to sever the tape after a strip of the desired length has been drawn from the spool—an operation which it is frequently inconvenient to perform, and further it is often necessary to use the tape when such cutting implements are not at hand. Also the spool if not enclosed when not in use is apt to become dirty so that its value for its intended purpose is considerably impaired owing to the unhygienic condition which the tape is then liable to have.

The principal object of my invention is to avoid the above inconvenient and objectionable features incident to handling tape of this character by providing a container for the tape so arranged that the tape will be normally completely enclosed while at the same time it may be readily got at when necessary; and by providing a cutter mounted as a unit with the container, and so arranged that a piece of tape when drawn off the spool may be easily and cleanly severed without distorting or pulling the tape out of shape.

The container and cutter are also so arranged that said cutter, which must be quite sharp to function efficiently, is normally sheathed so that the container may be carried in a pocket or otherwise handled without danger of the user being cut.

A further object is to arrange the container so that after a length of tape has been cut off, the adjacent end of the tape on the spool will remain where it is accessible for subsequent pulling or unrolling movement, without having to insert the fingers into the container. In connection with this feature I have provided means for positively pushing or prying said end of the tape clear of the container when it is desired to unroll another length of the tape, so that it may be then easily grasped without first having to pry up the tape with the finger-nail or other object.

A further object of the invention is to provide a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views.

Fig. 1 is a perspective view of the main unit of the container.

Fig. 2 is a similar view of the other unit which includes the cutter.

Fig. 3 is a perspective view of the completely assembled structure showing the cutter as operated on the tape.

Fig. 4 is a similar view showing the cutter in its fully retracted position.

Fig. 5 is a sectional elevation of the device showing the cutter as about to engage the tape.

Fig. 6 is a similar view showing the cutter in its retracted position, and with the edge of the tape raised by the automatically functioning finger.

Referring now more particularly to the characters of reference on the drawing the device comprises initially separate units.

One unit comprises an end head or disc 1 having a central core 2 of a size to freely project through the central core 3 of a spool of tape 4. A continuous band 5 somewhat wider than the spool of tape used is rigidly secured to the disc adjacent its rim, and projects from the same side as the core. The band 5 has a rectangular opening 6 slightly wider than the tape. One end E of this opening is parallel to the core or the axis of the container and forms a stationary cutting blade or edge. Disposed a short distance inwardly of the band and extending a short distance along the opening is a full-width lip 7, secured to said end E of the opening by a substantially radial shoulder 7a. Extending a short distance around the band from said end E of the opening in spaced and concentric relation to

the band is a sheath 8, which has the same width as the band.

The other unit of the structure comprises an end disc or head 9, the same size as the disc 1 and having a central hole 10 to freely receive the core 2. A segmental blade-band 11 curved concentric with the axis of the head is secured along one edge to said head; the inner radius of the blade being substantially the same as the outer radius of the band 5, so that it will lie directly on said band. One edge of the band 11 is sharpened as shown at 12, to form a cutting edge which extends on a transverse slant or diagonal from end to end. The long side of the blade band is the one which is secured to the head 9. A short distance beyond the cutting edge 12 a rigid arm 13 extends transversely of the unit from the head 9, and on its outer end carries a finger 14 which projects toward the blade. The arm and finger are disposed relative to the axis of the head so as to project inside the band 5 when the units are assembled; the finger being adapted to project through a slot 16 provided in the shoulder 7a of the lip 7 at one side of the same. Said finger is disposed relative to the blade and with respect to the length of the opening 6, so that the finger will only project through the slot when the blade is fully retracted from over the opening, as shown in Fig. 4.

When the units are placed together the core 2 is headed or crimped over the disc 9, so as to then prevent separation of the units, while keeping the one turnable relative to the other. The blade 11 is then disposed outwardly of the band 5, its side edge opposite to the head 9 being received and guided in a circumferential groove 15 formed in the disc 1 outwardly of the band 5. The free edge of the band 5 is similarly engaged with the head 9. The circumferential extent of this groove is sufficient to enable the blade to be moved from a fully retracted position to one in which the band 11 covers the opening 6 and the edge 12 is fully enclosed between the band and the sheath.

The rims of the heads or discs are nurled or otherwise roughened so as to provide a non-slip grip with the fingers.

When the device is not in use the opening 6 is covered by the blade 11 and the cutting edge is sheathed so that the interior of the container and the spool are protected from contamination from the exterior, and the user is protected from possibly being cut by the blade. When it is desired to cut a length of tape the blade is retracted from over the opening by holding one head in one hand and the other head in the other hand and rotating the one relative to the other the necessary extent. The end of the tape on the spool (assuming it is now a new spool) is pried up so that it can be grasped by the fingers and

is drawn off the spool in the direction opposite to the cutting blade; the spool rotating on the central core 2. After the tape has been unwound sufficiently to provide a strip of the desired length it is drawn snugly across the lip and the adjacent end of the sheath 8, and is also pressed down on the sheath for a short distance in adhering relation thereto, as shown in Fig. 5. The cutter is then advanced over the opening by relative rotation of the head until the blade cuts through the tape from edge to edge, when the cutting edge of the blade becomes again automatically sheathed. This cutting action is sure and clean on account of the double cutting edge or support for the tape formed by the edge E of the opening 6 and the adjacent edge of the sheath 8, between which the blade closely passes. The piece of tape cut may be then withdrawn and used as required. If there is no use for further strips of the tape at the time the blade remains in its sheathed and opening-covering position to which it was moved during the cutting operation.

When it is desired to cut off another strip of tape the blade is retracted from over the opening, as previously described. Owing to the sticky nature of the tape it will have remained adhered to the lip 7, in the same position as when previously cut. In retracting the blade so as to clear the opening however the finger 14 projects through the slot 16 and in so doing engages and raises the adjacent edge of the tip clear of the lip as shown at 17 in Figs. 4 and 6. This provides a tab for engagement with the fingers and it is an easy matter to then disengage the remainder of the width of the tape from its adhesion with the lip and unwind a length from the spool for cutting in the manner previously described. This disengaging operation is facilitated by the position of the ledge relative to the band 5, since the tape remains stretched from the free edge E (at which the cutting action took place) and a pocket, the bottom of which is at all times clear of the tape, remains under the tape adjacent said edge E. Once the edge of the tape has been raised by the finger 14, it is therefore an easy matter to pull the tape loose from the narrow surface with which it is still adheringly engaged.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An adhesive-tape container and cutter including a circular band having an opening therein and adapted to surround a spool of tape, means mounted in connection with the band for supporting a spool in turnable relation to the band to enable a length of tape to be unwound from the spool while being drawn through the band-opening, a blade member curved concentric with the band and disposed immediately adjacent the same and means mounting the blade in connection with the band for movement over the opening and beyond one end thereof, said end forming a fixed blade to cuttingly cooperate with the movable blade, whereby the projected tape will be severed by the relative movement of the blades into overlapping relation with each other. 70
2. A structure as in claim 1, in which the cutting edge of the movable blade extends diagonally of the band from side to side to provide a shearing action when said blade is turned to cooperate with the fixed blade. 75
3. An adhesive-tape container and cutter including a circular band having an opening therein and adapted to surround a spool of tape, means mounted in connection with the band for supporting a spool in turnable relation to the band to enable a length of tape to be unwound from the spool while being drawn through the band-opening, a blade member turnable on and concentric with the band and arranged for movement over the opening and beyond one end of the same, a sheath mounted on the band and extending from said end of the opening beyond the same a sufficient distance to enclose the cutting edge of the blade; said end of the opening and the adjacent end of the sheath being spaced apart to snugly receive the blade therebetween whereby said ends form fixed blades to cooperate with the movable blade. 80
4. An adhesive-tape container and cutter including a circular band having an opening therein, and adapted to surround a spool of tape, means mounted in connection with the band for supporting a spool in turnable relation to the band to enable a length of tape to be unwound from the spool while being drawn through the band-opening, a blade member turnable closely on and concentric with the band and arranged for movement over the opening and beyond one end of the same, the cutting edge of the blade then operating with the said end of the opening to sever a strip of tape drawn off the spool through the opening and abutted against said end of the opening, and means provided with the band for supporting the portion of the tape which extends from the spool to said end of the opening after the length of tape outwardly of the opening has been cut from the remainder. 85
5. An adhesive-tape container and cutter including a circular band having an opening
- therein, and adapted to surround a spool of tape, means mounted in connection with the band for supporting a spool in turnable relation to the band to enable a length of tape to be unwound from the spool while being drawn through the band-opening, a blade member turnable closely on and concentric with the band and arranged for movement over the opening and beyond one end of the same, the cutting edge of the blade then operating with the said end of the opening to sever a strip of tape drawn off the spool through the opening and abutted against said end of the opening, and a transverse lip fixed with the band and extending part way along the opening from said end thereof and disposed on a level inwardly of the band. 90
6. An adhesive-tape container and cutter including a circular band having an opening therein and adapted to surround a spool of tape, means mounted in connection with the band for supporting a spool in turnable relation to the band to enable a length of tape to be unwound from the spool while being drawn through the band-opening, a blade member turnable closely on and concentric with the band and arranged for movement over the opening and beyond one end of the same, and a member mounted in fixed connection with the band in outwardly spaced relation to the same sufficient to snugly receive the blade therebetween; the said end of the opening and the adjacent end of said member lying in a substantially common radial plane to form fixed blade elements to cooperate with the movable blade. 95
7. An adhesive-tape container and cutter including a circular band having an opening therein, and adapted to surround a spool of tape, means mounted in connection with the band for supporting a spool in turnable relation to the band to enable a length of tape to be unwound from the spool while being drawn through the band-opening, a blade member turnable closely on and concentric with the band and arranged for movement over the opening and beyond one end of the same, the cutting edge of the blade then operating with the said end of the opening to sever a strip of tape drawn off the spool through the opening and abutted against said end of the opening, and means provided in common movable relation with the blade for prying up the portion of the tape still connected to the spool and adjacent its severed edge when the blade is retracted from its cutting position. 100
8. An adhesive-tape container and cutter including a circular band having an opening therein, and adapted to surround a spool of tape, means mounted in connection with the band for supporting a spool in turnable relation to the band to enable a length of tape to be unwound from the spool while being

drawn through the band-opening, a blade member turnable closely on and concentric with the band and arranged for movement over the opening and beyond one end of the same, the cutting edge of the blade then co-operating with the said end of the opening to sever a strip of tape drawn off the spool through the opening and abutted against said end of the opening, and, a finger mounted in common movable relation with the blade in opposed relation to the cutting edge thereof and inwardly of the band; said finger being arranged, when the blade is retracted clear of the opening, to project into the opening from the cutting end of the same to pry up the portion of the tape still connected to the spool and adjacent the opening and severed edge of said tape portion.

20 In testimony whereof I affix my signature.
